Primary Examiner — Barbara Fox*Assistant Examiner* — Amanda Kay Birdwell(74) *Attorney, Agent, or Firm* — Hartman Titus PLC; Joseph W Mott(57) **CLAIM**

The ornamental design for a wine case, as shown and described.

DESCRIPTION

FIG. 1 is a rear perspective view of a wine case;

FIG. 2 is a bottom perspective view thereof;

FIG. 3 is a top view thereof;

FIG. 4 is a bottom view thereof;

FIG. 5 is a right-side view thereof;

FIG. 6 is a front view thereof;

FIG. 7 is a rear view thereof; and,

FIG. 8 is a front perspective view thereof, shown with the top flaps closed.

The broken lines showing bottles in FIGS. 1 and 3 represent environmental structure. All other broken lines represent the bounds of the claim. The broken lines form no part of the claimed design.

1 Claim, 7 Drawing Sheets(56)
